KNEE PAD

John S. Walker, Pittsburgh, Pa.

Application April 10, 1935, Serial No. 15,699

5 Claims. (Cl. 2—24)

The invention relates to knee pads and more especially to knee rests and protectors.

The primary object of the invention is the provision of a device of this character, wherein the knee of a user will be protected in the wearing thereof for any type of work requiring kneeling; such as, floor finishers, plumbers, tile setters, roofers, carpet layers, housemaids, etc., the device in its entirety being of novel construction.

Another object of the invention is the provision of a device of this character, wherein the pad proper carries a saddle for accommodating the knee, the said saddle being suitably lined to avoid discomfort to a wearer or injury to the knee cap or leg and the wearer may walk freely or assume a standing position without derangement of the pad when in this position.

A further object of the invention is the provision of a device of this character, wherein the construction thereof assures absolute protection to the knee of the wearer from all sharp or rough surfaces or from hot surfaces where the knee is in danger of being injured or bruised from weight.

A still further object of the invention is the provision of a device of this character, which is extremely simple in construction, thoroughly reliable and efficient in its operation, strong, durable, readily and easily applied to and removed from a wearer and inexpensive to manufacture.

With these and other objects in view, the invention consists in the features of construction, combination and arrangement of parts as will be hereinafter more fully described, illustrated in the accompanying drawings, which disclose the preferred embodiment of the invention and pointed out in the claims hereunto appended.

In the accompanying drawings:

Figure 1 is a vertical sectional view through the device constructed in accordance with the invention and applied to the leg of a wearer and illustrated in kneeling position.

Figure 2 is a side elevation of the device when the leg is straight.

Figure 3 is a sectional view on the line 3—3 of Figure 1 looking in the direction of the arrows.

Figure 4 is a front elevation.

Figure 5 is a side elevation showing the leg in kneeling position.

Figure 6 is a front elevation of a slight modification.

Figure 7 is a side elevation thereof.

Similar reference characters indicate corresponding parts throughout the several views in the drawings.

Referring to the drawings in detail, particu-

larly Figures 1 to 5, inclusive, the device which constitutes a knee rest or pad, comprises sections 10 and 11, respectively, these preferably being made from metal although the same may be made from any other suitable material satisfying the requirements in the use of the device. The section 10 has its body curved or shaped in conformity with the conformation of the knee at the cap thereof and interiorly of this body 10 is a fibrous lining or a felt pad 12 covering a major portion thereof and adapted to have contact with the knee of the wearer of the device when in kneeling position, the body 10 being formed with the tapered ends 13 these pivoted at 14 exteriorly to the section 11. This section 11 has a shape approximating the conformation of the fore part of the leg below the knee cap and carries within the same a saddle or hammock 15 provided with a lining 16 in the form of a pad or a soft covering for contact directly with the leg so that when the leg is in kneeling position this saddle or hammock 15 will be occupied thereby. The section 11 has formed therein a central opening 17 for accommodating a cork 18 which is the tread member of the pad or rest 15 although it may be otherwise fixedly held. The cork 18 is preferably made from resilient material although it may be otherwise constructed.

The pivot 14 is in the form of a separable fastener and is selectively engageable in spaced holes 19 as provided in the section 11 at each side thereof so that the section 10 can be adjusted or regulated with respect to the section 11 according to the requirements of the wear of the device.

Formed on the section 10 is an upstanding outwardly tapered extension 20 through which is laced at the slots 21 therein a leg embracing band 22 it having suitable separable connectors 23 for the fastening of the band 22 about the leg or its removal therefrom.

The section 11 has the outwardly tapered end portions 24 with which is connected a leg embracing band 25 carrying separable fasteners 26. This band is also adapted to embrace the leg and by these straps 22 and 25 the device is made secure upon the leg of the wearer.

The device in the wearing position thereof both when kneeling and standing erect is clearly disclosed in Figures 1 and 2 of the drawings.

In Figures 6 and 7 of the drawings there is shown a slight modification wherein the section 27 which is similar to the section 11 has at the

fore upper part thereof a slot 28 accommodating a hanger strap 29 through which is trained the leg embracing strap 30, the section 10 being entirely eliminated in this modified form of device.

5. What is claimed is:

1. A device of the kind described, comprising a rigid body section having an opening therein, a calk fitted within the body section and extending through the opening, a saddle hung within the body section and holding the calk in the opening and means for detachably securing the body section to a leg to have the same rest within the saddle next to the knee cap of said leg.

10. 2. A device of the kind described, comprising a rigid body section having an opening therein, a calk fitted within the body section and extending through the opening, a saddle hung within the body section and holding the calk in the opening, means for detachably securing the body section to a leg to have the same rest within the saddle next to the knee cap of said leg and a cushioning lining fitted within the saddle.

15. 3. A device of the kind described, comprising a rigid body section having an opening therein, a calk fitted within the body section and extending through the opening, a saddle hung within the body section and holding the calk in the opening, means for detachably securing the body section to a leg to have the same rest within the saddle next to the knee cap of said leg, a cushioning lining fitted within the saddle, a knee cap protective section swingingly connected with the body

section and working exteriorly thereof and means for strapping the last-named section to the leg.

4. A device of the kind described, comprising a rigid body section having an opening therein, a calk fitted within the body section and extending through the opening, a saddle hung within the body section and holding the calk in the opening, means for detachably securing the body section to a leg to have the same rest within the saddle next to the knee cap of said leg, a cushioning lining fitted within the saddle, a knee cap protective section swingingly connected with the body section and working exteriorly thereof, means for strapping the last-named section to the leg, and linkage between the said sections. 5

10. 5. A device of the kind described, comprising a rigid body section having an opening therein, a calk fitted within the body section and extending through the opening, a saddle hung within the body section and holding the calk in the opening, means for detachably securing the body section to a leg to have the same rest within the saddle next to the knee cap of said leg, a cushioning lining fitted within the saddle, a knee cap protective section swingingly connected with the body section and working exteriorly thereof, means for strapping the last-named section to the leg, linkage between the said sections and a cushioning lining carried by the last-named 15 section. 20
